UNITED STATES PATENT OFFICE.

AUGUST J. BERG, OF CHICAGO, ILLINOIS.

AUTOMATIC CAR-BRAKE.

SPECIFICATION forming part of Letters Patent No. 288,298, dated November 12, 1883.

Application filed October 28, 1882. (No model.)

To all whom it may concern:

Be it known that I, AUGUST J. BERG, a citizen of the United States of America, residing at Chicago, in the county of Cook and State of Illinois, have invented an Improvement in Automatic Car-Brakes, of which the following is a specification, to wit:

This invention relates to automatic car-brakes; and it consists in the combination, 10 with a paper pulley placed on one of the axles, of a friction-wheel adapted by the slackening of the speed of the train to be engaged with a paper pulley on the axle, and having a train of gearing or similar mechanism, by which the 15 brakes are applied automatically when the friction-wheel and pulley are in contact.

It also consists in a novel clutch, by which the friction-wheel is engaged with its shaft, and also in a novel device by which the friction-wheel may be thrown into or out of gear, for running in either direction, from the outside of the car, as will be hereinafter more fully explained.

In order to enable others skilled in the art 25 to which my invention appertains to make and use the same, I will now proceed to describe its construction and operation, referring to the accompanying drawings, in which—

Figure 1 is a plan view of a car having my 30 improvements attached; Fig. 2, a longitudinal section of the same; Fig. 3, a detail perspective view of the hub of the friction-wheel with its clutch; Fig. 4, a view of the device by which the friction-wheel is set in operation 35 in either direction; Fig. 5, a view of the paper pulley with one of the metal ends removed; Fig. 6, a front elevation of the same; and Fig. 7 a vertical section of part of the same, showing the manner of tightening it upon the axle.

40 A represents a car-frame, which is mounted upon wheels A', as usual, and provided with a draw-bar, B, having a bumper-spring, b, and all of the usual or any desired construction. I employ, as is usual in automatic 45 brakes of this class, a rod, C, secured to a movable head within the coupler, and running back through the draw-bar, having its outer end passing through a lever, C', pivoted in the frame at one end, and its opposite end 50 moving freely in a horizontal direction. Around the rod C, between the lever C' and the

draw-bar, is a coiled spring, c, which is compressed by a key, c', by the backward movement of the rod, and acts on the lever C' to throw its outer end backward. d' is a clip, 55 pivoted to the lever C' between its fulcrum-point in the main frame and the rod C, and actuated by a spring, a', coiled around its shank, which always holds the lever C' in its extreme forward position when the brake is 60 not in operation.

Mounted in a frame, D, just over one of the axles, A', is a shaft, d, on one end of which is a pinion, d', meshing with a spur-wheel, d'', on a shaft, d''. To this shaft d'' is secured a 65 chain, e, the other end of which is connected to the upper end of a lever, E, fulcrumed in a casting on one of the cross-bars, E', to which the brake-shoes E'' are attached, and extending a suitable distance below this fulcrum-point, where it is connected by a bar, E'', to the other brake-bar, E', as seen in Fig. 2. The opposite end of the shaft d is supplied with two clutches, D' D'', between which is a 70 loose wheel, D'', which is thrown into gear 75 with one or other of the clutches D' by means of an angle guide-lever, F, fulcrumed at f in the end of a rod, f', which has a rocking motion in the frame D. This guide-lever F has upon one end a fork, f'', which engages with 80 a groove, f''', in the hub of the wheel D'', and its opposite end is connected by a link or rod, g, with a cranked shaft, G, which passes transversely across the frame from side to side, and is provided on each end with a handle or 85 pointer, G', by which it may be turned to actuate the angle or draw guide-lever F, and slide the wheel D'' on the shaft d, as may be desired. On the outside of the main frame A, on one 90 side, is placed a piece of notched metal, g', with which the handle G' on that end of the rod G engages, as seen in Fig. 4, and is held in engagement by a coiled spring, g'', on the shaft G, between one of the supporting-brackets, G'', and a collar, g''', on the shaft.

The end of the shaft d, upon which the wheel D'' is placed, is supported by the horizontal arm of an angle or bell-crank lever, H, fulcrumed in the frame D, and having the upper end of its perpendicular arm formed with an eye, h, through which passes the end of a rod, I, which is formed in two parts swiveled to

gether, as seen in the drawings, and the forward end is flattened, as seen at i , and rests in a stirrup, i' , secured to the forward end of the frame. The extreme forward end of the 5 swiveled rod I is formed with a crank, i^2 , to which is connected a rod, i^3 , extending to the roof of the car. The rod I runs under the outer end of the lever C', and is here provided with a finger, I', curved upward and backward, which engages the rear side of the lever, as seen in the drawings. The flattening of the rod at i serves to hold it from turning accidentally after being set. The inner end of the rod, where it passes through the eye h, is 15 headed or provided with a pin, which prevents its being withdrawn from the eye, and is held in its forward position by a spring. This serves to hold the friction-wheel D² from contact with the friction-pulley on the axle 20 during the forward motion of the train, and when this rod is pushed back, allowing the wheel D² to drop, the rod slides freely through the eye and applies no pressure to the wheel. 25 The clutches D' D' are formed as seen in Fig. 3, having on their inner faces circular springs k, which are secured on one side in a groove in the face of the clutch, and are formed with an angular bend, k', which forms a shoulder, which engages with a similar shaped 30 depression, k², on the adjacent face of the hub of the wheel D². When in its normal position the spring k is flush with the face of the clutch, with its shoulder projecting, and when pressed the spring recedes within the groove in the 35 clutch until the shoulder k' is entirely inclosed. By the cranked shaft G and angle-lever F, the wheel D² is thrown into gear with one of the clutches D' when the train is running in one direction, and in the opposite direction to engage with the other clutch when 40 running in the reverse direction.

The axle A², just under the friction-wheel D², is provided with a paper pulley, L, formed in two parts, as seen in Fig. 5, and secured 45 by a plate, L' L', on each side. These plates L' are formed in two parts, as shown, having overlapping edges l l, which are drawn together to tightly fit the axle by a wedge-bolt, m, passing through the paper pulley L, and 50 through slots in the overlapping edges of the plates L', as seen in Fig. 7. When the train is running the friction-wheel is held from contact with the pulley L by the head or pin in end of rod I, acting on the lever H. When it is desired to stop the train the engine is slowed or steam is shut off entirely, when the cars running upon the engine will push upon each other, the coupling-links drive back the rods C, which moves the lever C', and by its engagement with the rod I, drops the friction-wheel D² on the pulley L, where it is held by its own weight, and operates the pinion d' and spur-wheel d² to apply the brakes. It will be observed that no damage can be caused by 55 too much movement of the rods I, as they slide through the eye h, as shown by dotted lines in Fig. 2, and puts no pressure upon the fric-

tion-wheel beyond its own weight. The friction-wheel may be set to operate in either direction from the outside of the car by means 70 of the handle G', and this handle may be turned in a perpendicular position and allow the friction-wheel to run free in either direction during switching or similar operations. The rod I, being swiveled and provided with 75 a crank and rod connecting with the top of the car, may also be turned over by a brakeman upon the roof of the car, so that the finger I' will not engage with the lever C', and thus throw the brakes out of gear for backing 80 or switching without getting off the cars.

Having thus fully described my invention, what I claim as new, and desire to secure by Letters Patent, is—

1. In an automatic car-brake, a friction-wheel 85 running loosely upon its shaft and provided with means for shifting it from side to side, in combination with two clutches secured upon the shaft, and adapted to engage with the wheel to operate it in opposite directions, substantially as shown and described. 90

2. In an automatic car-brake, a clutch consisting of a disk having a concentric groove in its inner face, in which is secured a spring-ring formed with a bend or shoulder, which is normally projected beyond the face of the disk, but when yielding to pressure will sink entirely within the groove, in combination with the shaft d and loose wheel D² on the shaft, the loose wheel D² being thrown into gear with the clutch, 100 substantially as shown and described. 95

3. The combination, in an automatic car-brake, of a friction-wheel running loosely upon its shaft and formed with a curved and inclined depression in each side of its hub, terminating in a shoulder at opposite ends, in combination with the shaft having two disks formed with concentric grooves, in which are secured spring-rings having angular bends or shoulders adapted to engage with the depressions in the hub of the friction-wheel as it is thrown from one side to the other, and thus operate the shaft in either direction, substantially as described and shown. 110

4. In an automatic car-brake, an operating-shaft provided with two clutches operating in opposite directions, and a friction-pulley running loosely between them, in combination with a cranked shaft extending transversely across the car-frame, and connected by a link 120 or rod with an elbow guide-lever adapted to throw the friction-wheel into gear with one or other of the clutches as the cranked shaft is turned, substantially as shown and described. 115

5. In an automatic car-brake, the cranked rod G, having handles G', collar g², and retracting-spring g³, in combination with the bracket G² and notched plate g¹, all constructed and arranged to operate substantially as shown and described. 125

6. In an automatic car-brake, the operating-rod I, formed in two parts, swiveled together and provided with a curved finger, I', in combination with the lever C', operated by a push-

bar within the draw-head, substantially as described and shown.

7. In an automatic car-brake, the rod I, formed in two parts swiveled together, the forward part having a finger, I', and formed with a crank, i², on its end, connected by a rod, i³, with the top of the car, whereby the rod may be turned to engage with or be disengaged from the lever C', substantially as and for the purpose set forth.

8. In an automatic car-brake, the operating-shaft d, having one end journaled in the frame D and the other carried by one arm of an elbow-lever, H, the other arm of which is formed with an eye, h, in combination with the rod I, passing loosely through the eye h and retracted by a coiled spring, whereby the friction-wheel D² is normally held from contact with the pulley upon the axle, and when released is held in contact only by its own weight, substantially as and for the purpose described.

9. In an automatic car-brake, the combination, with a shaft having one end journaled in an elbow-lever and provided with two clutches, and a loose friction-wheel having an endwise movement upon the shaft to engage with either one of the clutches, of an elbow guide-lever adapted to slide the friction-wheel upon its shaft, and fulcrumed in the end of a shaft hav-

ing a rocking movement in the supporting-frame as the friction-wheel rises and falls, substantially as shown and described.

10. In an automatic car-brake, the combination, with the push-bar C, provided with a spring, c, with the lever C', fulcrumed in the frame at one end and formed with an eye, through which the push-bar passes, and the clip a', having spring a² for returning the lever to its normal position, substantially as described and shown.

11. In an automatic car-brake, the car-frame A, having draw-bar B and mounted upon the wheels A¹, one axle of which is provided with a friction-pulley, L, in combination with the push-bar C, having spring c, lever C', jointed and swiveled rod I, with finger I', elbow-lever H, shaft d, carrying the clutches D', friction-wheels D², and pinion d', spur-wheel d² upon the shaft d³, chain e, lever E, brake-bars E', having connecting-rod E¹, and brake-shoes E², all constructed and arranged to operate substantially as and for the purpose set forth.

In testimony whereof I affix my signature in presence of two witnesses.
